UNITED STATES PATENT OFFICE

2,635,187

BROAD BAND ANTENNA

Arthur Dorne, Freeport, N. Y., assignor to the
United States of America as represented by the
Secretary of War

Application March 29, 1946, Serial No. 657,939

2 Claims. (Cl. 250—33)

1

This invention relates generally to electrical apparatus and more particularly to antennas.

In some antenna applications the number of desirable characteristics of an antenna may become numerous.

For example, the antenna may be required to meet rigid specification regarding such characteristics as directivity, band width, polarization, input impedance, and physical size and weight. Additional characteristics of antenna which may determine its usefulness in applications, such as radio frequency direction finding systems, relates to the constancy of the shape of the antenna response pattern as the operating frequency is varied. Generally, the shape of an antenna pattern varies substantially as the operating frequency is varied.

In many antenna applications, direction finding systems for example, a shifting antenna pattern is undesirable and may admit confusion in the interpretation of the intelligence presented by the radio frequency apparatus.

It is an object of the present invention to provide an antenna particularly adapted for use with radio frequency direction finding systems.

It is also an object to provide an antenna whose response pattern remains substantially constant in shape over a wide range of operating frequencies.

An antenna, which accomplishes the aforesaid objects, consists of a balanced, sleeved, dipole with four auxiliary stub radiators attached to the dipole. A center fed dipole has its central portion enclosed concentrically in a metallic sleeve which has a large circumference with respect with its length. The ends of the dipole, which protrude beyond the ends of the sleeve, are enlarged to approximately the size of the sleeve. At each end of the sleeve, two auxiliary stub radiators are attached to the dipole. These stubs are oriented perpendicularly with respect to the longitudinal axis of the dipole and all four stubs are in the same geometric plane.

Other objects, features and advantages of this invention will suggest themselves to those skilled in the art and will become apparent from the following description of the invention taken in connection with the accompanying drawings in which:

Fig. 1 is an elevation of an antenna embodying the principles of this invention; and Fig. 2 is an end view of Fig. 1.

Referring now to Fig. 1, a balanced dipole consisting of dipole elements 10 and 11 has its central portion concentrically enclosed by a metallic

2

sleeve 12. The outer ends of dipole elements 10 and 11 are enlarged to approximately the size of sleeve 12. Two auxiliary radiator stubs, 13 and 14, are connected to dipole element 10 perpendicular to the longitudinal axis of dipole element 10, near one end of sleeve 12. Similarly, two auxiliary radiator stubs 15 and 16 are connected to dipole element 11. Stubs 13, 14, 15 and 16 are all in the same geometrical plane. This sleeved dipole antenna is center fed and two conductors, 17 and 18 respectively, of a balanced two wire transmission line, are inserted through holes in sleeve 12, and connected to the dipole elements. Conductor 17 is connected to an end of dipole element 10 and, similarly, conductor 18 is connected to dipole element 11.

Referring now to Fig. 2, an end view of Fig. 1 is shown and the same reference numbers used in Fig. 1 are again repeated.

Generally, the radiation characteristics of an antenna, when used for transmitting, are similar to the response characteristics of that antenna when used as a receiving antenna. Consequently, for the purpose of explanation, the device of this invention will be considered as a transmitting antenna.

Conductors 17 and 18 apply equal and opposite voltages to dipole elements 10 and 11. The enlarged ends of dipole elements 10 and 11 radiate some energy into space but their principal function is to electrically excite sleeve 12, which contributes most of the radiation from this antenna. Having a large surface area and a large periphery compared to its length, sleeve 12 is closely coupled to space and hence, readily radiates any radio frequency energy induced on it.

If the bidirectional characteristics of this antenna pattern are to be utilized, the antenna should be oriented so that the four stubs 13, 14, 15 and 16 are in a plane which is perpendicular to the desired directions of maximum radiation. The total length of the antenna should be of the order of one-third of a wavelength corresponding to the lower operating frequency. The length of each of stubs 13, 14, 15 and 16 should be about one-tenth of a wavelength corresponding to the abovementioned lowest operating frequency.

It has been found experimentally that the addition of stubs 13, 14, 15 and 16 to the dipole elements, substantially influences the antenna pattern characteristics. These stubs have no pronounced effect other than to control the radiation pattern of the antenna. When these four stubs are used with the antenna, the radiation pattern of the antenna maintains a substantially

constant shape as the operating frequency is varied over wide ranges. With conventional antennas, when the operating frequency is varied over wide ranges, the antenna pattern often changes rapidly in directivity, the magnitude of minor lobes vary, and the main lobe may even split into several secondary lobes.

The principle of operation of these stubs 13, 14, 15 and 16 is not at the present time well understood, however, it has been established experimentally that the use of these stubs does allow an antenna to be used over wider ranges of frequency, before the shape of the antenna pattern becomes distorted.

The antenna herein disclosed has been used with a small section of a parabolic reflector to obtain a broad band, unidirectional antenna for use with direction finding systems.

In this particular application, the antenna operated over a frequency range of approximately 5 to 1, and within this frequency range the lobe pattern remained substantially constant in shape and the gain of the antenna was equal to or better than that of a standard dipole in free space.

While there has been here described what is at present considered to be the preferred embodiment of the invention, it will be obvious to those skilled in the art that various changes and modifications may be made therein without departing from the scope of the invention as set forth in the appended claims.

What is claimed is:

1. A broad band directional plane polarized antenna including a center fed exciter dipole having outer ends larger in diameter than the central portion, a tubular conductive sleeve radiator concentrically enclosing the central portion of said dipole, and a plurality of stubs connected to said dipole near the ends of said sleeve radiator, the longitudinal axis of each of said stubs being perpendicular to the longitudinal

axis of said dipole whereby the shape of the response pattern of said antenna is directional and remains substantially constant throughout the operating frequency band.

5. 2. A plane polarized antenna with a substantially constant directional radiation pattern over a broad operating frequency band including a pair of center-fed exciter dipole elements having a total length approximately one-third of a wavelength corresponding to the lowest operating frequency and outer ends of larger diameter than the central portions, a metallic sleeve radiator concentrically enclosing and insulated from the central portions of said dipole elements with the enlarged ends of said dipole elements extending beyond the ends of said sleeve radiator, four identical cylindrical stubs each having a length approximately one-tenth of a wavelength corresponding to the lowest operating frequency, two of said stubs being connected to one of said dipole elements near an end of said sleeve radiator and two of said stubs being connected to the other of said dipole elements near the other end of said sleeve radiator, each of said four stubs being oriented perpendicularly with respect to the longitudinal axis of said dipole elements and all of said stubs being in the same geometrical plane, and a two-wire feed line connected to said dipole elements near their centers.

ARTHUR DORNE.
